UNITED STATES PATENT OFFICE.

ALBERT HENNIG, OF HAMBURG, GERMANY.

DOUBLE-ACTING TWO-STROKE-CYCLE INTERNAL-COMBUSTION ENGINE.

1,210,801.

Specification of Letters Patent.

Patented Jan. 2, 1917.

Application filed August 28, 1912. Serial No. 717,507.

To all whom it may concern:

Be it known that I, ALBERT HENNIG, a subject of the Emperor of Germany, residing at Hamburg, Germany, have invented 5 certain new and useful Improvements in Double-Acting Two-Stroke-Cycle Internal-Combustion Engines, of which the following is a specification.

This invention relates to double-acting 10 two-stroke cycle internal combustion engines with pistons running in opposite directions and controlling the admission and exhaust-ports, and relates to an engine of this kind wherein there are provided a large double- 15 acting working-piston controlling the scavenging air ports and four smaller single-acting pistons of shorter stroke than the double-acting working piston, which smaller pistons have their axes parallel and control 20 the exhaust ports, the compression chambers being each bounded by two small pistons and the large working piston. By thus distributing the exhaust over two pistons of shorter stroke than the large working piston, 25 ton, the exhaust-ports can be made shorter than would be the case if the said exhaust-ports were arranged in the working cylinder, and the bridges between the ports can consequently cool rapidly, since the heat can 30 be conducted away more easily to the adjacent metal of the cylinders. Moreover on account of the short-stroke exhaust-pistons, the height of the engine can be reduced. Furthermore the scavenging air ports can 35 be made much longer and can have a larger cross-section than the exhaust-ports and will consequently allow the scavenging air to pass in very quietly.

In the accompanying drawing, I have 40 shown how my said invention may be conveniently and advantageously carried into practice.

In this drawing, *a* is the working piston movable in a cylinder *a'* having a centrally- 45 arranged annular series of ports *a²*, *a²*, which communicate with an annular chamber *a³* extending around the cylinder *a'*. This chamber *a³* and ports *a²*, *a²*, preferably serve 50 for the introduction into the cylinder *a'* of the scavenging air. These ports *a²*, *a²*, are controlled by the working piston *a* whereby they are opened to the spaces at opposite ends of the cylinder *a'* alternately.

The cylinder *a'* is in communication at 55 each end through passages *c*, *c* with two cylinders *b'*, *b'*, in which move single-acting

pistons *b*, *b* controlling annular series of ports *b²*, *b²*, which communicate with annular chambers *b³*, *b³*, extending around the cylinders *b'*, *b'*, respectively. The said annular chambers preferably communicate with the exhaust.

The several pistons above mentioned are driven from a crank shaft *d*, the crank *d'* of which drives the working piston *a* and 65 the cranks *d²*, *d²*, which are arranged at an angle of 180° to the crank *d'* and are of shorter throw, drive the pistons *b*, *b*. The said crank-shaft may be connected to said pistons by suitable intermediate gearing of 70 known construction, for example, in such a manner that, at each end of the working cylinder *a'*, the working piston *a* moves first toward and then away from the pistons *b*, *b*. The fuel may advantageously be injected 75 through the passages *e*, *e*, for example, in the case of ignition by the heat of compression, when the pistons *a*, *b*, *b* are in the position shown in the upper part of the figure, the injection of fuel into the lower combustion-chamber *c* taking place when the crank-shaft has turned through an angle of 80 180°.

It is known that in two-stroke-cycle engines, especially in those which work with compression-ignition (Diesel), the efficiency 85 and the quality of the combustion are dependent on the completeness of the scavenging.

In order to obtain good scavenging, the 90 scavenging air must be prevented from mixing with the gaseous products of combustion, *i. e.* penetrating into them and thus only diluting them, the intention being to expel the gaseous products of combustion by means of the scavenging air without the 95 latter mixing with them. For this purpose, the scavenging-air ports *a²*, *a²*, should only be opened by the working piston *a* after a part of the exhaust gases has escaped through 100 the exhaust ports *b²*, *b²*, and the pressure in the working cylinder *a'* corresponds to the pressure of the scavenging air. In the engine shown in the accompanying drawing, on account of the considerably greater stroke 105 of the scavenging air-piston *a*, the scavenging air ports *a²*, *a²*, are longer than the exhaust-ports *b²*, *b²*, and also larger scavenging areas are opened much more rapidly than in the case with the usual two-stroke

cycle arrangements. Notwithstanding the 110 shorter stroke of the exhaust pistons *b*, *b*, the cross-sections of the exhaust ports *b²*, *b²*,

are still large enough, since the circumference of the cylinder is the determining factor for the cross-section of the port and the combined circumference of the two exhaust cylinders b', b' is considerably greater than that of only one of the same total cross-sectional area.

By reason of the greater stroke of the scavenging air piston a considerably greater 10 and more rapidly opening cross-sections of port are thus obtained. It is to be assumed that in each case the scavenging air cylinder space is well scavenged. Only in the case where the scavenging air passes over 15 from the scavenging air cylinder a' into the two exhaust cylinders b', b' , is eddying to be feared on account of the change of direction which the exhaust gases experience. It is to be assumed that the exhaust cylinders 20 are worse scavenged than the scavenging air cylinders. For that reason in the new arrangement the volume of the exhaust cylinder is kept as small as possible and the stroke reduced.

25 It is known that the cylinders of double acting engines, by reason of the rapid generation of heat, are very liable to be injured by excessive temperatures, especially when it is sought to obtain higher mean pressures.

30 Now it has not heretofore been possible in practice to make the linings of the cylinders of double-acting two-stroke-cycle engines freely extensible in a satisfactory manner. These excessive temperatures result in warping 35 and cracking of the cylinder more especially at the ports, which either cannot cool at all or can only partly cool. The hot gases do not reach the scavenging air ports because they are already on their way toward 40 the open exhaust ports before the former are opened. Since the latter is also cooled from the interior in the usual manner with water, undesirable transmission of heat to the stuffing boxes is not to be feared.

45 The temperature of the scavenging air sweeping along the cylinder will gradually rise, the exhaust cylinders will become the hottest and damage can here be avoided in a known manner, by freely expansible cylinder-linings. The expansion of the cylinders by reason of the exhaust-cylinders being short will be very small, the short exhaust-cylinders will easily cool completely and the short, small exhaust pistons are 50 more certain in operation than one large one, especially with the short stroke.

55 In motors with compression-ignition, which are designed for propelling ships, the slow speed causes trouble. The compression chamber with the slow speed and the low mean pressures soon becomes so cold

that ignition does not take place. This cooling of the compression chamber is increased by the fact that, with a two-stroke-cycle, the scavenging air, and with a four-stroke-cycle, 65 the air drawn-in, is almost always introduced directly into the compression-chamber, so that here the air, where it is still the coolest, impinges against the walls of the compression-chamber. In the new engine, 70 the compression-chamber is kept warm by the main body of the hot exhaust gases which there give up a large part of their heat by reason of the alteration of direction and the eddying. Also the scavenging air which 75 follows is here already so preheated that no considerable lowering of temperature can occur during slow running.

Engines the cylinders of which have their axes parallel, especially those with short-stroke exhaust-cylinders, can be easily dismounted. Also in the present arrangement one has a large amount of freedom in respect of the dimensions of the crank-shaft. If the scavenging and exhaust-cylinders are 85 coaxial, the centers of the three-throw crank fall too near together. A further advantage of the new arrangement is that all the cylinders and also the engine-frame are relieved 90 from the load due to the force exerted by the piston. The piston-forces are transmitted directly by the linkwork to the three-throw crank-shaft. The new engine by reason of the short stroke of the exhaust piston is built 95 very short. It is of course also possible to control the exhaust ports by the large double acting piston and the air ports by the four small pistons with parallel axes.

Claim:

In a double acting, two-stroke cycle internal combustion engine having cylinders provided with scavenging air and exhaust ports, the combination of a large double acting working piston controlling the scavenging air ports with four similar smaller single 100 acting working pistons, said smaller pistons having parallel axes, a shaft, a central crank on said shaft, said double acting working piston being connected to said central crank arranged at an angle of 180° to said first 105 named crank, means for connecting the smaller pistons to said cranks, two of said smaller pistons and the working piston bounding each of the compression chambers of the engine, substantially as described. 110

In testimony whereof I affix my signature in presence of two witnesses.

ALBERT HENNIG.
